UNITED STATES PATENT OFFICE.

SAMUEL ALLEN BATES, OF ST. LOUIS, MISSOURI.

SURGICAL APPLIANCE.

Application filed October 12, 1922. Serial No. 594,128.

To all whom it may concern:

Be it known that I, SAMUEL A. BATES, a citizen of the United States, and a resident of St. Louis, in the State of Missouri, have 5 invented certain new and useful Improvements in Surgical Appliances, of which the following is a specification.

This invention relates to surgical appliances and more particularly to a device for 10 use in connection with surgical operations on the intestines and where such operations necessitate the severing of the intestine.

An object of the invention is the provision of a thimble for maintaining the severed 15 ends of an intestine, especially the ileum, distended after a surgical operation has been performed for the relief of intussusception and after the ends of the intestines have been connected by a cat gut suture.

20 A further object of the invention is the provision of a thimble for the purpose, which is adjustable in line with the longitudinal axis of the thimble in order that said thimble may be accommodated to intestines 25 of various sizes.

A further object of the invention is the provision of a thimble formed of a substance which will melt at the proper time due to the heat of the body and 30 be passed from the intestines, or which is capable of removal from the intestines in a normal manner by the use of a medicinal preparation acting as a lubricant rather than as a purgative.

35 Other objects and advantages of the invention will be apparent during the course of the following description.

In the accompanying drawings forming a part of this specification, and in which like 40 reference numerals designate like parts throughout the same,

Figure 1 is a side view of a portion of the intestine which has been severed and connected by cat gut suture showing my invention in position.

45 Figure 2 is a longitudinal section of the same showing my invention as applied to a severed portion of the intestine.

Figure 3 is a view in perspective of the 50 thimble.

Figure 4 is a longitudinal section of the same.

Referring to the drawings; 1 indicates a 55 thimble which is cylindrical in shape, made of some flexible material which is capable of being melted by the heat of the human

body or which may be removed from its position in the intestines in a normal manner by the use of a medicinal preparation. The material of which the thimble is composed may be wax, paraffin or soft rubber.

The wall of the cylinder is split along its longitudinal axis with the end 2 of the split portion overlapping the other end 3 of the split portion. The end 2 of the split portion is gradually reduced in thickness toward its outer edge 4 whereby the split cylinder with the overlapping ends 2 and 3 form substantially a cylindrical thimble which is adapted to be inserted between the 70 severed ends of an intestine.

Midway of the open ends of the thimble 1 and upon the outer wall of the same is formed an annular rib 5 with the inner wall of said rib provided with an annular groove 75 6. The portions of the wall of the thimble on opposite sides of the rib 5 are depressed as shown at 7 and 8 forming annular grooves upon the outer wall of the thimble. The continuation of the rib 5 on the end 3 of the split portion of the cylinder is adapted 80 to be received within the groove 6 of the rib, which is continued on the other end 2 of the split portion of the cylindrical member 1.

The opposite peripheral edges of the thimble are beveled as shown at 9 whereby the ends 10 and 11 of the intestine may be readily slipped over the opposite ends of the thimble.

On opposite sides of the rib 5 are formed a pair of openings 12 which are adapted to receive a thread of cat gut 13 forming the suture whereby the ends of the intestine are connected together and by which the thimble 1 is anchored in position at the rupture of the intestine. While I have shown a pair of perforations only, I wish it to be understood that any number of perforations may be used which may be necessary to properly anchor the thimble in proper relation with the rupture of the intestines which have been connected together by the suture.

105 The overlapping ends 2 and 3 of the thimble permits a decreasing of the cylindrical circumference where the thimble is employed with intestines of smaller sizes, with said ends sliding over each other after such reduction.

110 The thimble may be made of soft rubber, paraffin or wax and is adapted to be em-

ployed for distending the severed portions of the intestines which have been secured together by a cat gut suture after an operation for intussusception of the bowels which frequently occurs near the ileocaecal valve.

Where intussusception of the ileum occurs due to various causes adhesion of the ileum frequently takes place and the adhesions are broken up by a dull instrument and the invaginated ileum is drawn back in place. If it be found that the ileum is of too great a length, such unnecessary length of the ileum is removed. The thimble is slipped into place as shown in Figure 2 with the severed ends of the intestine forced over the beveled ends 9 of the thimble until the severed ends of the intestine are located in end to end engagement with each other at the rib 5 of the thimble. The engaged ends of the intestine are sewed together by means of cat gut with a thread passing through the perforations 12 whereby the thimble is anchored in position within the intestine.

By pressing upon opposite walls of the thimble 1 the diameter of the thimble may be sufficiently reduced that the thimble may be readily inserted within the severed ends of the intestines with ease. By relieving pressure on opposite points of the wall of the thimble the resilience of the thimble will cause the same to expand and neatly fit the inner wall of the intestine and thereby prevent leakage through the intestine at the severed portions. The cat gut suture will hold the ends of the intestine together while the intestine is healing, but the thimble, when made of paraffin or wax will eventually melt or become sufficiently soft whereupon it will be normally removed from the ileum. Where a rubber thimble is employed the same may be removed by treating the patient with olive oil until the thimble has passed from the ileum.

The thimble just described is not only adapted for use in operations for intussusception of the intestines but may be also employed in connection with any other operation where portions of the intestines are removed or severed. The thimble may be employed in operations for the relief of persons suffering from gun shot wounds of the intestines.

The annular grooves 7 and 8 are depressed sufficiently in the wall of the thimble to form a pair of parallel ribs on the inner wall of the thimble. These ribs on one overlapping portion of the thimble are adapted to seat in the grooves 7 and 8 of the other split portion and are slideable in said grooves when the thimble is formed to accommodate a cylinder of smaller diameter.

The operation for intussusception of the bowels is performed on the small intestine at the ileocaecal valve and a blunt instru-

ment is employed to break up the adhesion of the invaginated intestine. This portion of the bowel is then withdrawn from its telescoping position and as much of the elongated intestine is removed as is sufficient to prevent a recurrence of intussusception.

What I claim is:

1. A surgical appliance for use in connection with surgical operations on the intestines, comprising a cylindrical member made of flexible material having its walls split along the longitudinal axis of the cylinder, with the split ends located in overlapping relation and slideable on each other whereby the circumference of the cylinder may be varied to fit intestines of different sizes, an annular rib formed on the outer wall of the cylinder midway of its ends, the opposite ends of the cylindrical member being beveled, the rib being provided with a groove on its inner wall with an end of the groove on one split portion of the cylinder adapted to receive the opposite end of the rib on the other split portion of the cylindrical member, the end of the outer overlapping split portion of the cylinder being gradually reduced in thickness toward its edge, said rib being provided with perforations for receiving the cat gut suture employed for connecting the severed ends of an intestine for anchoring the cylinder in place in an intestine.

2. A surgical appliance for use in connection with surgical operations on the intestines, comprising a cylindrical member made of flexible material having its walls split along the longitudinal axis of the cylinder, with the split ends located in overlapping relation and slideable on each other whereby the circumference of the cylinder may be varied to fit intestines of different sizes, an annular rib formed on the outer wall of the cylinder midway of its ends, the opposite ends of the cylindrical member being beveled, the rib being provided with a groove on its inner wall with an end of the groove on one split portion of the cylinder adapted to receive the opposite end of the rib on the other split portion of the cylindrical member, the end of the outer overlapping split portion of the cylinder being gradually reduced in thickness toward its edge, said rib being provided with perforations for receiving the cat gut suture employed for connecting the severed ends of an intestine for anchoring the cylinder in place in an intestine, the wall of the cylindrical member being provided with grooves located upon opposite sides of the annular rib, one of the overlapping portions of the split cylindrical member being provided with grooves on opposite sides of the rib, with ribs formed on the inner wall of the other overlapping portion of the cy-

lindrical member and seated within the intergrooves of the first mentioned overlapping portion.

3. A surgical appliance for use in connection with surgical operations on the intestines comprising a cylindrical member made of flexible material having its walls split along the longitudinal axis of the cylinder with the split ends located in overlapping relation and slidable on each other whereby the circumference of the cylinder may be varied to fit intestines of different sizes, said cylinder being provided with perforations adapted to receive certain of the cat gut sutures employed in connecting the severed ends of an intestine for anchoring the cylinders in place in the intestine.
4. A surgical appliance for use in connection with surgical operations of the intestines comprising a cylindrical member made of flexible material, a rib formed on the outer wall of the cylindrical member and intermediate its ends, a plurality of perforations formed in the wall of the cylinder adjacent the rib for receiving a portion of the cat gut suture employed in connecting the severed ends of an intestine.
5. A surgical appliance for use in con-

nection with surgical operations of the intestines comprising a cylindrical member 30 made of flexible material, a rib formed on the outer wall of the cylindrical member and intermediate its ends, a plurality of perforations formed in the wall of the cylinder adjacent the rib for receiving a portion 35 of the cat gut suture employed in connecting the severed ends of an intestine, the opposite ends of the cylinder being beveled.

6. A surgical appliance for use in connection with surgical operations on the intestines comprising a cylindrical member made of flexible material having its walls split along the longitudinal axis of the cylinder with the split ends located in overlapping relation and slidable on each other 40 whereby the circumference of the cylinder may be varied to fit intestines of different sizes, said cylinder being provided with perforations adapted to receive certain of the cat gut sutures employed in connecting the 45 severed ends of an intestine for anchoring the cylinders in place in the intestine, and a rib on the outer wall of the cylindrical member located intermediate the ends of said cylinder.

SAMUEL ALLEN BATES.
